UNITED STATES PATENT OFFICE.

DAVID WALKER AND ROBERT H. WARREN, OF NEWARK, NEW JERSEY.

DESIGN FOR A STAIR-CARPET BUTTON.

SPECIFICATION forming part of Design No. 23,628, dated September 4, 1894.

Application filed August 9, 1894. Serial No. 519,881. Term of patent 7 years.

To all whom it may concern:

Be it known that we, DAVID WALKER and ROBERT H. WARREN, citizens of the United States, residing at Newark, in the county of Essex and State of New Jersey, have invented and produced a new original Design for Stair-Carpet Buttons; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan showing our design, and Fig. 2 is a central section of the same, these two views being deemed necessary to fully illustrate our design.

The leading feature of the design consists in a stair button, on the face of which is displayed, near the periphery, a series of bead-shaped ornaments, and radiating from the

center, a series of petal-shaped ornaments alternating with long rays.

a, indicates a round stair button, around 25 the central perforation, *c*, of which is displayed the series of petal-shaped ornaments, *b*, the petals alternating with longer rays, *c*. Near the periphery is displayed a series of bead-shaped ornaments, *d*, which terminate 30 in dots or smaller beads, *f*, between the peripheral beads.

What we claim as new is—

The design for a stair button, herein shown and described.

In testimony that we claim the foregoing we have hereunto set our hands this 3d day of August, 1894.
